BOOKSTACK

William C. Bond, Washington, D. C.

Application June 28, 1937, Serial No. 150,793

23 Claims. (Cl. 211—135)

(Granted under the act of March 3, 1883, as
amended April 30, 1928; 370 O. G. 757)

The invention described herein may be manufactured and used by or for the Government of the United States for governmental purposes without the payment to me of any royalty thereon.

The object of this invention is to provide simplicity in construction and erection of a type of multi-tiered convertible bookstack which includes in its design means within the building structure for ventilation of the superimposed decks.

Another object is to provide a design of multi-tiered bookstacks in which the elements that are used to provide supports for the books can be readily compacted or removed and the space used for other purposes.

While another object is to provide vertical supports, for supporting the superimposed decks and the bookstacks therein, which are adapted to form conduits for air conditioning the decks, housing for water and electricity conduits, as well as housings, conduits or passageways for other equipment usually necessarily exposed in building structures.

Other objects and purposes of my invention will become apparent from the following description and the accompanying drawings, it being understood that the above general statements of the objects of my invention are intended to broadly explain the same without limiting it in any manner.

The accompanying drawings are illustrative examples of building and bookstack structures having the characteristics of my invention and by which the same may be practiced.

Figure 1 is an elevational view of a section of a vertical hollow column and of bookshelf supporting panels next above and below one floor level of a tier, the floor and horizontal supporting bars or beams being in cross section. Figure 1 is taken at line 1—1 of—

Figure 2, which illustrates a cross-sectional view taken at line 2—2 of Figure 1 and terminating at 2'—2' thereof.

Figure 3 is a perspective of a section similar to that shown in elevation in Figure 1.

Figure 4 is a vertical sectional view taken at line 4—4 of Figure 3.

Figure 5 illustrates an adjustable spacer carried by the shelf-supporting panel for spacing the same from the vertical column.

Figure 6 is a perspective illustrating a section of one tier of the assembled bookstack.

Figure 7 is a view in perspective of a section of

a horizontal Z-bar adapted to support floor plates and shelf-supporting panels.

Figure 8 is an elevational view of portions of the face of the shelf-supporting panel illustrating, in cross section, the application of a shelf-dividing barrier or curtain. This view is taken at line 8—8 of—

Figure 9 which is taken at line 9—9 of Figure 8.

Figure 10 illustrates a cross-sectional view of a modified form of horizontal supports a portion of which is adapted to serve as a floor plate.

My invention comprises, as illustrated in the drawings, a vertical supporting column 10 having a pair of channel-formed beams 11 arranged so that the channel-forming flanges 12 of the respective beams project toward each other so that the corners of the channel beams form the corners of the column. (See Figures 2 and 3.) The beams 11 of each column are spaced from each other sufficiently to provide a column of desired or required width and/or sufficiently to provide a desired or required space area between and within the facing channels 13. The channel beams are retained in a predetermined vertical spaced relation by horizontal members 14, which are preferably angle irons. The angle irons are fixed horizontally, by such as bolts passing through the vertical leg 15 thereof, to the outer sides of the beam flanges 12, on opposite sides of the column 10, parallel to each other, preferably at floor levels, with their respective horizontal legs 16 uppermost and projecting laterally and outwardly in opposite directions from the sides of the column. If the channel beams 11 are spaced from each other sufficiently to cause a space between the edges of the flanges 12 of the respective beams, or, in other words, if the flanges 12 of the respective beams are of insufficient width to contact each other by reason of the spacing of the beams, then a filler plate or sheet of material 17 is fitted vertically between the edges of the respective flanges 12 and on a plane therewith supplementing the action of the angle iron in maintaining the spaced relationship of the channel-formed beam. The plates 17 are carried by, and vertically parallel to, the intermediate portion of the vertical leg 15 of the angle iron 14. The plates 17 are thereby fixed between the edges of the flanges 12 of the respective beams 11 at floor levels and serve as an enclosure for the hollow column at and through the floor levels where it is difficult to otherwise complete or continue the column enclosure.

Viewing a section of the column from a flange-formed side, as best seen in Figs. 1 and 3, the one flange 12 of each channel beam on one side of the column in combination with the interposed plate 17 form an H-shaped structure, the elements of which are in a single plane. A structure of similar configuration is formed, of course, on the opposite side of the column and the two H-shaped structures are spaced and connected by the integral webs of the channel beams 11 which form the other two sides of the column.

When the horizontal parallel angles 14 combined with plate 17 are bolted to the outer sides of the beam flanges 12 the plates 17 form continuous interposed surfaces with the flanges to which are applied panels 18. These panels extend from floor to ceiling and overlap a portion of the plates 17 and beam flanges 12 to which they are fixed by such means as bolts, spring clips, or screws.

By the structure thus far described the hollow column 10 is formed. The passageway 19 formed within the column may be used as an air conduit for air conditioning the structural area in which the column is utilized. By the term "air conditioning" it is intended to include cooling, heating by steam or hot air, ventilating, drying, humidifying and similar purposes to which air or gas may be used.

The passageway 19 may also be utilized for the housing and passage of conduits for electricity, air, steam or gas, and water or other liquids, and also as a passage and housing for vacuum or pressure tubes for cleaning and pneumatic carriers, as a passage and housing for article conveyors, and as a passage and housing for other equipment usually necessarily exposed in bookstack constructions as well as in other types of building structures.

The panels 18 are readily removable whereby free access to the passageway 19 and the equipment housed therein may be had for repairs, installation, for painting to prevent rusting and corrosion, for cleaning and the like.

When the passageways 19 are used as supply conduits for air conditioning, the columns 10 are provided with exhaust nozzles, jets, vents, ducts, or the like, 20 which communicate with the conduit. These exhaust nozzles, or the like, are preferably located near the top of the column 10, i. e., so much of the column as is within a deck. They may be provided with any suitable cut-off means or dampers whereby the exhaust ports may be entirely closed, decreased or restricted so their action can be made uniform not only over the entire deck but throughout the superimposed decks although the various exhaust ports may be served by the same conduit.

The nozzles are preferably provided with deflectors and are positioned near the top of the deck in order that the air exhausted from the columns may not directly strike an occupant or worker and in order that cooled or conditioned air exhausted therefrom may take its natural course and filter downwardly through the deck. In the use of the columns 10 for air conditioning, the column is also provided with intakes such as registers 21 preferably located near the floors of the decks for exhausting the air from the decks that is used as it filters down through the decks from the nozzles 20. The intake register 21 may preferably be located beneath the bookstacks, to be described hereinafter, and thereby draw any dust or the like, that ordinarily accumulates beneath shelves, into the conduit. This register is

also provided with suitable cut-off means or dampers for purposes similar to those stated in connection with the exhaust nozzles 20.

In order that there be no conflict in the cycle of the air, it is, of course, necessary that the intake register 21 communicate with a return conduit separate from the supply conduit. This is preferably accomplished by either omitting the intake register 21 from the columns supplying the exhaust nozzles 20 or if not omitted by closing the intake register 21 on the supply column and then reversing the order on some other column, preferably the next adjacent one, and utilizing the second column as an exhaust for drawing the air from the decks.

The construction of the type of column described provides a substantial vertical support for buildings, decks and framing members as well as for direct and indirect supports for shelf-supporting members for bookstacks. For the foregoing uses, like parallel columns are erected in straight lines at predetermined intervals and are connected in their relative positions by horizontally disposed means adapted to prevent lateral displacement of the columns and which are also adapted to support deck flooring as well as support shelf-supporting means to be described hereinafter. The latter horizontally disposed means may consist, as shown, of pairs of parallel and horizontal beams 22 attached to opposite edges of the columns at floor levels. These beams are formed so as to provide a vertical web portion 23 having horizontal flanges 24 and 25 projecting laterally, horizontally and at right angles to the vertical web but in opposite directions from the upper and lower edges of the vertical portion. The lower horizontal flange 25 is in turn provided at its outer edge with an upturned vertical portion 26 at right angles to the flange 25 and substantially parallel with the web portion 23. The beam is referred to hereinafter as a Zee, or Z beam. In the utilization of the Z beams one of each pair is reversed end for end in order that the horizontal flanges or legs 24 project in opposite directions. In the installation of the Z beams the ends are coped to fit the corners of the channel beams 11, i. e., the end portions of the horizontal flanges or legs 25 and the end portions of the vertical upturned flanges 26 are removed and the newly formed ends of the latter portions 25 and 26 are brought into contact with the outer sides of the flanges 12 of the channel beams, while the vertical webs 23 of the Z beam pass along the outer side of the web of the channel beams and are secured thereto. The upper horizontal flanges or legs 24 of the Z beam also continue along the edges of the columns 10 on a plane with the horizontal flanges or legs 16 of the angle irons 14 installed along the sides of the columns. A horizontal flange 60 thereby extends laterally from each edge and side of the columns at floor levels which flanges are adapted to support flooring or floor plates 27.

Additional means may be provided for supporting the floor plates, and load thereon, between the rows of columns and may consist as shown, of T-shaped beams 28. These beams are installed preferably from one row of columns to another and may be attached to the channel beams 11. The end portions of the T beams are 70 coped to fit the horizontal flanges 24 and contact the vertical flanges 23 of the Z beams, i. e., the end portions of the cross-bars 29 of the T beams are removed and the newly formed ends thereof are brought into abutment, and on a 75

plane with the horizontal flanges 24 of the Z beams 22 while the depending stem portions 31 of the T beams continue beneath the flange 24 and into contact with the web 23 of the Z beam. The T beam may be secured to the column by such means as a horizontally disposed bracket 30, or the like, one portion of which may be bolted to the depending stem 31 of the T beam and another through the vertical web 23 of the Z beam to the web of the channel beam 11.

The structure hereinbefore described, although adapted for use in general building construction, is particularly adapted for the support of and service to bookstacks, particularly bookstacks of the following character which is a part of my invention and adapted for conjoint use therewith.

My bookstack comprises a plurality of relatively thin uprights or shelf-supporting sections 32 disposed at predetermined intervals vertically between the columns 10 and transversely of the column-connecting Z beams. The sections 32 are preferably gridded in such a manner as to provide upper and lower end bar portions 33 and 34, side bar portions 35 and central bar portions 36. The openings 37 forming the gridded portion are preferably arranged in vertical and horizontal rows whereby there is provided vertical and horizontal supporting bar portions 38 and 39, respectively, connecting the upper and lower end bar portions 33 and 34 and the side and central bar portions 35 and 36.

Redescribed, the section 32 comprises a thin vertical panel-like section or upright having a yoke 33 across the upper end thereof with vertical side, central, and intermediate bar portions 35, 36, and 38 depending therefrom and horizontal bar portions 34 and 39 connecting the ends and intermediate portions of said side, central, and intermediate vertical bar portions 35, 36 and 38.

The sections 32 are carried by and upon portions of pairs of the overhead Z beams. To accomplish this the sections are provided with hooks or lugs 40, preferably trochoidal in shape formed in, on, by, or projecting from the ends of the upper end bar portion or yoke 33 which are adapted to engage and carry the sections 32 upon the horizontal and vertical flanges 25 and 26 of the Z beam 22. The sections 32 are provided with centrally located laterally projecting superposed lugs 41 and lugs or notches 42 on or in the edges of the section or side bar portions 35, which means 41 and 42 are adapted to receive and support ends, or means on the ends, of bookshelves disposed between adjacent shelf end supporting sections.

To locate and maintain the sections 32 on proper centers and prevent lateral displacement, the vertical upturned flanges 26 of the overhead Z beams 22 are provided with notches 43 at predetermined intervals, which notches are adapted to receive and retain the lug or hook portions 40 of the sections 32. In addition to the latter retaining means for the sections, other means are provided for locating and maintaining the lower ends thereof on proper centers, against swinging and against torsional or lateral displacement. These means may consist of a pair of horizontal bars or rails, preferably a pair of horizontally parallel angle rails 44 attached transversely across the lower edges of the sections. For attachment purposes, horizontally surfaced lugs 45, formed by projections or notches, are provided on the ends of the lower end bar portions 34 of

the sections and are formed so as to receive one leg of the angle rail transversely upon the surface of the lugs 45 with the other leg of the angle rail depending transversely across the ends of the lugs. The rails are then removably secured to the lugs by means such as screws 46 passing either through holes, located at predetermined intervals on a center line vertically coinciding with the notches 43 in the Z beam, in the horizontal flanges of the angle rail and into the surface of the lugs or through holes in the vertical flanges of the rails into the ends of the lugs. These section-tying and positioning rails 44 extend from one column 10 to another but are not secured thereto, they are instead coped or notched to contact and fit against and about the corners of the channel beams 11 of the columns which may be accomplished by removing a sufficient portion of the horizontal flanges of the rail 44 to allow the same to fit horizontally between two columns, and thereby prevent a longitudinal movement of the assembled bookstack. The vertical flanges of the rails are allowed to extend along the outer surface of the web of the channel beams 11 and thereby form means for preventing edgewise movements of the sections or the assembled bookstack.

It will thus be seen that this construction provides a most simple and accurate means for assembling a convertible bookstack and maintaining its upright members in alignment. The uprights are held absolutely on their proper centers at each of their corners, and twisting or warping is prevented by the rails 44 being notched at their ends over the channel beams 11.

In order to remove a book range it is only necessary to remove the screws 46 which fasten the parallel angle rails 44 to the upright sections 32. The upright sections may then be lifted out of the notches 43 and compacted one against the other or turned slightly and removed entirely for the utilization of the space between the columns for other purposes. No part of the bookstack proper is attached or fastened to the structural members, the bookstack being merely supported upon and braced against the overhead horizontal beams and vertical columns. Slight variations in the structural members can occur without in any way affecting the proper alignment of the bookstack since its alignment is controlled by properly locating the notches 43, the holes in the angle rails 44 and the notches on the ends of the rails 44.

A modified type of horizontal supports for the floor plates and upright sections is illustrated in Figure 10. By reference thereto it will be seen that in lieu of the Z bars 22, I propose to utilize a horizontal support having a pair of vertical webs 23', a pair of horizontal flanges 25', similar to those respective members of each pair of Z bars 22. The horizontal flanges 24 of the Z bars are, however, omitted in this modification and the vertical webs 23' continue into a connecting floor plate 27' and at right angles thereto. At the junction between the vertical webs 23' of this modification, and the floor plate 27', an exterior right angular indentation 24' is provided for the receipt and support of the next adjacent floor plates 27.

The metallic dividing curtains 47 shown in Figures 8 and 9, are for the purpose of dividing any double-faced bay of the bookstack into two separate parts. The addition of removable doors to the half sections convert them into locked compartments.

- The curtains 47 are provided at their upper ends with a reinforcing T-shaped strip 48. The stem 49 of the T-shaped strip is either double or provided with a groove into which the upper edge of the curtain is inserted and secured to the embracing stems 49 of the T-shaped strip. The cross head and divided stems of the T-shaped strip are allowed to project beyond the edge of the curtain where the pair of stems are spread jaw-like, as at 50 of Figure 9, beneath the cross head which caps the opening between the jaws 50. Similar jaws 51 at the bottom of the curtain are also provided and allowed to project from the edges of the curtain. The lower jaws 51 are formed by strips applied to the opposite faces of the curtain and their projecting ends flared or spread. At their lower ends the steel curtains are bent back on themselves and thence at right angles to the panel to provide the necessary stiffness to the bottom of the curtain and also to provide a horizontal member 52 adapted to project beneath the lower shelf 53 indicated in dotted lines, Figures 8 and 9. Lugs 54 and 55 adapted to receive the jaws 50 and 51 are provided on the central bar portion 36 of the upright sections 32 preferably between the rows of superposed shelf-supporting lugs 41. In position, lateral displacement of the curtain is prevented by the jaws while a downward displacement is prevented by the projecting cross head of the T-shaped strip 48 which rests upon the lug 54 and supports the curtain thereon. An upward displacement of the curtain is prevented when the lower shelf 53 is in position and overrides the horizontal flange 52 of the curtain. Detachable doors (not shown) may also be provided and pivoted in holes 56 provided in the horizontal flanges 25 of the Z bars 22 and in the horizontal flanges of the angle rails 44. When the doors are locked it is then impossible for the lower shelf to be moved forward and the curtain is therefore locked in place without the necessity of using any separate applied mechanical fastenings.
- 45 The upright sections 32 on the ends of the ranges may not always fall in contact with the columns 10, by reason possibly of slight variations in structural manufacture, and in order to prevent a lateral flexing of the upright sections 50 toward the columns, counter-sunk screws 57 are provided (see Figures 5 and 6) in the side bar portions 35 of the sections, which screws are threaded through the bar portions and adjusted to bear against the passageway column and thereby retain the section against an outward lateral flexing, i. e., toward the column.
- What I claim is:
1. A rectangular structural column having a passageway therethrough, comprising a pair of spaced channel-formed beams disposed to have their webs form the respective edges of the column and disposed to have their respective pairs of flanges project toward each other to form side portions of said column, in combination with a pair of panel-like members attached to the respective sides of said column by means removably connecting the side of said panel-like members to the outer sides of the column side-flanges, and plate-like means disposed intermediate the edges and in the plane of said column side-flanges and inwardly overlapping ends of side panel-like members.
2. A rectangular vertical structural column, having a passageway therethrough comprising a pair of spaced channel-formed beams, the flanges

of which form side portions of said rectangular column, in combination with a plurality of pairs of panel-like members vertically superposed upon the respective sides of said column and applied to the outer sides of said channel beams in the manner of a fishplate, and plate-like members interposed between and in the plane of the flanges to inwardly overlap the ends of said superposed panel-like members.

3. A rectangular structural column having a passageway therethrough comprising a pair of spaced channel-formed beams disposed to have their webs form the respective edges of the column and disposed to have their respective pairs of flanges projecting toward each other to form side portions of said column, in combination with a pair of panel-like members removably attached to the respective sides of said column, spacing means applied to the outer sides of said column at intervals therealong and connecting said flanges, a plate carried by each of said spacing means designed to fit between the edges of said flanges and to inwardly overlap ends of said panel-like members.

4. A rectangular vertical structural column having a passageway therethrough, comprising a pair of spaced channel-formed beams, the webs and flanges of which form side portions of said rectangular column, in combination with floor supports along the flange formed side of the column and attached to said flanges and constituting spacing elements for said channel beams at floor levels along said vertical column, and plates lying in the plane of said flanges and attached to each said floor supports and extending above and below said supports to form with said webs and flanges a smooth rectangular column extending through said floors, and a panel-like member overlapping said plates and said flanges to form a passageway within the column between floors.

5. A rectangular vertical structural column having a passageway therethrough, comprising a pair of spaced channel-formed beams, the webs and flanges of which form side portions of said rectangular column, in combination with plates lying in the plane of said flanges at floor levels along said column and forming with said webs and flanges a smooth rectangular casing at said floor levels, panel-like members overlapping said plates and said flanges forming a substantially rectangular casing between said floor levels.

6. Building construction including a hollow structural column formed of a pair of channel-formed beams the webs and flanges of which define the sides of the column, and a pair of horizontal parallel floor supporting beams each having a portion passing along and attached respectively to the webs of said channel beams at opposite sides of the column, in combination with a pair of horizontal parallel spacing members attached to the flanges of said channel beams at the other sides respectively of the column, said spacing members having floor supporting flanges forming a planer surface with said floor supporting beams.

7. Building construction including a hollow structural column formed of a pair of spaced channel-formed beams the webs and flanges of which define the sides of the column, and horizontal parallel supporting beams attached to and supported by the webs of said channel-formed beams, in combination with horizontal bar-like supporting members attached to the flanges of said channel-formed beams and located between

5 said horizontal supporting beams, plate-like members carried by said bar-like members and located between the edges of the flanges of said channel-formed beams, and a panel-like member in overlapping engagement with said flanges and said plate-like members.

8. Building construction including a vertical hollow structural column comprising a pair of channel-formed beams the corners of which form the corners of said column, and a pair of angle iron supports disposed horizontally along opposite sides of the column with their horizontal legs uppermost, in combination with a pair of supporting beams each having a vertical web and an upper and lower flange projecting reversely from said web, said lower flange being coped to allow the upper flange and the vertical web of the beam to pass along the side of the column at right angles to said angle iron supports and to allow 10 its lower flange to abuttingly contact the side of the column, and means passing through the webs of the supporting beams and the web of the channel beams for supporting the upper flanges of said supporting beams on a plane with the 15 horizontal legs of the angle iron supports.

9. Building construction including a vertical hollow structural column comprising a pair of channel-formed beams the corners of which form the corners of said column, and a pair of 20 angle iron supports disposed horizontally along opposite sides of the column with their horizontal legs uppermost, in combination with a pair of supporting beams having vertical webs and upper and lower flanges coped to allow the upper flanges and the vertical webs thereof to pass along the sides of the column at right angles to said angle iron supports and to allow their lower flanges to abuttingly contact the sides of the column, means passing through the web of the 25 supporting beams and the web of the channel beams for supporting the upper flanges of said supporting beams on a plane with the horizontal legs of the angle iron supports, additional supporting beams having vertical webs and horizontal flanges, said horizontal flanges being copied to transversely abut against the horizontal flanges of said pair of supporting beams with the vertical webs of the additional supporting beams transversely in abutment with the vertical webs of the 30 pair of supporting beams, and means for supporting the horizontal flanges of said additional supporting beams on a plane with the horizontal legs of the angle iron supports and the upper flanges of said supporting beams.

55 10. Building construction peculiarly adapted to support library book-shelves including a vertical column, a pair of supporting beams each having a vertical web and an upper and lower flange extending reversely from said web, said lower flange being coped to allow the upper flange and the vertical web of each beam to pass along the side of the column and to allow its lower flange to abuttingly contact the side of the column, and a shelf support carried upon and depending from the lower flanges of said supporting beams.

60 11. Building construction adapted to support bookracks including a vertical column, a pair of supporting beams having vertical webs and each having an upper horizontal flange projecting from one side of said web, and each having a lower flange projecting from the other side of said web, said lower flanges being coped to allow the upper flanges and the vertical webs of the beams to pass along the sides of the column and to allow their lower flanges to abuttingly con-

tact the sides of the column, the lower flanges of said supporting beams being provided with an upturned serrated edge, and a shelf support interlocking with said serrations and depending from the lower flange of said beam.

5

12. An end section for bookstacks and means for supporting the same comprising a substantially rectangular panel and spaced parallel beams, means on the face and edges of said panel for supporting shelves, and a lug located at each 10 upper outer corner of said panel, said panel being supported in tension upon said beams by said lugs acting in shearing stress.

13. An end section for bookstacks and means for supporting the same comprising a substantially rectangular panel and spaced parallel beams, means on the face and edges of said panel for supporting shelves, a trochoidal shaped lug located at each upper outer corner of said panel resting on said beams and constituting the sole 20 supporting means for supporting said panel in tension.

14. An end section for bookstacks and means for supporting the same comprising a substantially rectangular panel and spaced parallel beams, means on the face and edges of said panel for supporting shelves, and trochoidal shaped lugs on said panel acting in shearing stress upon said beams and suspending said panel in tension.

30 15. A bookstack comprising a pair of parallel spaced elevated beams supported by upright members, and shelf supporting panels supported solely by said beams, said panels being provided at their upper ends with yoke-like portions bridging the space between said elevated beams, the 35 ends of said yoke-like portions resting upon said beams and suspending said panels in tension.

16. A bookstack comprising a pair of parallel spaced beams elevated by supports, shelf supporting panels provided at their upper ends with 40 yoke-like portions bridging the space between said elevated beams, the ends of said yoke-like portions resting upon said beams and suspending said panels in tension, and means upon said elevated beams engaging the sides of said yoke-like 45 portions to maintain the upper ends of said panels in parallel alignment.

17. A bookstack comprising a pair of parallel spaced beams elevated by supports, shelf supporting panels provided at their upper ends with 50 yoke-like portions bridging the space between said elevated beams, the ends of said yoke-like portions resting upon said beams and suspending said panels in tension, means upon said elevated beams engaging the sides of said yoke-like 55 portions to assist in the maintenance of said panels in spaced parallel alignment, and spacing means engaging said panels at points removed from and cooperating with said latter means to maintain said panels in spaced parallel alignment.

60 18. A bookstack comprising a pair of spaced vertical columns, a pair of spaced elevated horizontal supports spanning and secured to said columns, shelf supporting panels provided at their upper ends with yoke-like portions bridging the space between said elevated supports with their end portions supported on said supports and suspending said panels in tension, and means engaging said panels at their lower ends and said columns to hold said panels in fixed spaced 65 70 relation to each other and to said columns.

19. In combination with end sections for a bookstack, lugs centrally located on said end sections near the top and bottom thereof, and a metallic curtain, means on the curtain near the 75

bottom thereof engaging the sides of said lower lugs, and means on the curtain near the top thereof engaging the top and sides of said upper lugs.

5. 20. In combination with end sections for a bookstack, shelves carried by said end sections, lugs centrally located on the faces of said end sections near the top and bottom thereof, a metallic curtain positioned between said end sections, the lower portion of said curtain being bent back upon itself and provided with a laterally projecting flange engaging the lower surface of one of said shelves, reinforcing members attached to said bent back portion and extending beyond opposite ends of said curtain for engagement with the sides of said bottom lugs, and a reinforcing T-shaped member having bifurcated leg engaging opposite sides of the upper edge portion of said curtain, end portions of said T-shaped member extending beyond the opposite ends of said curtain and engaging the top and sides of said upper lugs.
10. 21. In combination with end sections for a bookstack, lugs centrally located on said end sections near the top and bottom thereof, a metallic curtain the lower end of which is bent back
15. 20. 25.

upon itself, means attached to said bent back portion, extending beyond the ends of said curtain, and engaging the sides of said bottom lugs, and a reinforcing member of pressed sheet metal engaging the top of said curtain, extending beyond the ends thereof, and engaging the top and sides of said upper lugs.

5. 22. In combination with end sections for a bookstack, lugs centrally located on the end sections near the top and bottom thereof, a metallic curtain provided with reinforcing members extending beyond the ends of said curtain with the extending portion of one of said reinforcing members in engagement with the sides of one of said bottom lugs and that of the other in engagement with the top and sides of one of said upper lugs.

10. 23. In combination with end sections for a bookstack each having a lug centrally located near the top thereof, a metallic curtain provided with a head and side reinforcing member extending beyond the ends thereof and in engagement with the top and sides of said lugs, and means for locking said curtain in position.

15. 20. 25. WILLIAM C. BOND.
